UNITED STATES PATENT OFFICE.

ELLSWORTH H. SEBRING, OF SEBRING, OHIO, ASSIGNOR TO THE E. H. SEBRING CHINA COMPANY, OF SEBRING, OHIO, A CORPORATION OF OHIO.

DESIGN FOR A COVERED DISH.

Application filed December 2, 1926. Serial No. 19,903. Term of patent 7 years.

To all whom it may concern:

Be it known that I, ELLSWORTH H. SEBRING, a citizen of the United States, residing at Sebring, in the county of Mahoning and State of Ohio, have invented a new, original, and ornamental Design for Covered Dish, of which the following is a specification, reference being had to the accompanying drawing, forming part hereof.

Fig. 2, a side elevation of the covered dish.

I claim:

The ornamental design for a covered dish, as shown.

ELLSWORTH H. SEBRING.
